Patented July 4, 1967

208,020

AUTOMATIC ANIMAL FEEDER

Joseph F. Woerner, 823 Azalea, Houston, Tex. 77018

Filed Feb. 16, 1966, Ser. No. 1,070

Term of patent 3½ years

(Cl. D12—2)

Fig. 1

Fig. 2

Fig. 3

Fig. 4

FIG. 1 is a front and right end perspective view of an automatic animal feeder, showing my new design;

FIGURE 2 is a rear and left side perspective view;

FIGURE 3 is a top view;

FIGURE 4 is an enlarged fragmentary view of the upper part thereof.

I claim:

The ornamental design for an automatic animal feeder, as shown.
